BY

Duull, Warfalo & Duull

ATTORNEY

UNITED STATES PATENT OFFICE.

WILLIAM A. GREEN, OF TORONTO, ONTARIO, CANADA.

HOLDER.

Application filed November 6, 1919. Serial No. 336,222.

To all whom it may concern:

Be it known that I, WILLIAM A. GREEN, a subject of Great Britain, residing at Toronto, in the Province of Ontario and 5 Dominion of Canada, have invented certain new and useful Improvements in Holders, of which the following is a full, clear, and exact description, such as will enable others skilled in the art to which it appertains to 10 make and use the same.

This invention relates to dishes comprising holders and paper linings therefor.

One of the objects of the invention is the provision of a practical service receptacle 15 in which ice cream and the like may be conveniently served in a cleanly and sanitary manner.

Another object of the invention is the provision of an efficient paper blank capable of being readily shaped into an elongated dish lining adapted to hold ice cream 20 and the like.

The invention accordingly consists in the features of construction, combinations of 25 elements and arrangement of parts which will be exemplified in the construction hereinafter described and the scope of the application of which will be indicated in the following claims.

30 In the accompanying drawing forming part of this specification and wherein similar reference characters refer to similar parts throughout the several views,

Figure 1 is a side elevation of a holder 35 and a paper dish lining operatively associated therewith;

Fig. 2 is a plan view of the holder;

Fig. 3 is a view of a paper blank from 40 which the paper dish lining may be formed; and

Fig. 4 is a transverse section through the holder showing certain dish lining stops on the edge of the holder.

Referring now more particularly to Fig. 45 1, there is illustrated a metallic holder composed of a base 1 and a body 2. The numeral 3 indicates a paper dish lining seated in the body of the holder.

In the present embodiment the base and 50 the body of the holder are made of thin metal pressed into shape and brazed or otherwise connected together at the line 4. The body of the holder is shaped to provide the elongated concavity comprised between 55 the end walls 5 and the side walls 6, the end walls curving transversely of the

holder and being relatively steeply pitched as compared with the sides of the holder, which latter are more gently inclined. The sides 5 merge into each other along a central longitudinal line, and the entire concavity is smooth and free from sharp angles so that it may be readily cleaned. Preferably also, the bottom of the concavity inclines gently downwardly from the central 60 line 7 toward the apices 8 where the walls 5 and 6 merge therewith. The numeral 9' indicates an opening which communicates with the hollow base portion. At this point it may be observed that the hollow 70 base portion 1 is open at the bottom.

The opposite sides 6, 6, of the holder each have inwardly extending stops 9 and 10 to cooperate with the edge of the paper dish lining and retain the latter in position. 75 As illustrated, these stops are at the end of the walls of the concavity and may be formed by turning inwardly a portion of the metal of such edges. Between the stops and the ends of the body of the 80 holder the edges of the holder may be cut away, as illustrated, to give shapeliness to the body and to economize in metal.

The blank for the dish lining is illustrated 85 in Fig. 3. As shown, it is a generally elliptical sheet having at each end free overlapping contiguous portions, as by longitudinally slitting at each end from its edges along the lines 11 to points 12 which are 90 designed to rest adjacent the apices 8, 8 of the holder. The blank for the dish lining is made of paper of some resiliency, so that when the blank is pressed into the 95 holder as hereinafter explained, free portions thereof, as the tongues 13 and 14 at each side of the slits 11, will be caused to overlap each other and lie against the end walls 5 of the concavity of the body. The sides of the blank are inwardly recessed as indicated at 15 for engagement with the stops 100 9 and 10. In the blank illustrated the recesses 15 are rather sharply cut in the edge of the blank, but it is to be understood that the full lateral edges of the blank may be 105 curved inwardly and thereby provide such recesses. In operation, one of the flat blanks described may be selected from a pile at hand and placed over the concavity in the body of the holder. By then pressing down at the points 12 the blank may be 110 thrust into the concavity and seated therein, the tongues 13 and 14 automatically over-

lapping as the points 12 on the blank are pressed towards the apices 8, 8 hereinbefore referred to. The operation of seating the blank in the holder will cause the opposite 5 sides of the blank to assume position beneath the stops 9 and 10, whereupon the paper dish lining and holder will be in operative position ready for use with the blank bent across the central line. Longi- 10 tudinal movement of the dish in the holder will be restrained to a sufficient extent by the edges of the paper blank which provide shoulders 16, as it were, at each side of the stops 9 and 10. Also the tendency of the 15 blank to unfold is restrained by the stops.

Thus by the above described construction are accomplished, among others, the objects hereinbefore referred to.

As many changes could be made in the 20 above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent, is:-

1. In a device of the character described, a holder including an elongated concavity the end walls of which curve transversely of the holder, the side walls having inwardly extending stops, in combination with a resilient paper dish lining seated in said concavity with its edges beneath said stops, said dish lining comprising free overlapping contiguous portions lying against the end walls and held in position by engagement therewith.

2. In a device of the character described, a holder including an elongated concavity the end walls of which curve transversely of the holder, the side walls having inwardly extending stops, in combination with a resilient paper dish lining seated in said concavity with its edges beneath said stops, said dish lining comprising free overlapping tongues lying against the end walls of said concavity, said dish lining being slit from its edge at opposite ends to provide said tongues.

3. In a device of the character described, a holder including an elongated concavity the end walls of which curve transversely of the holder, the side walls having inwardly extending stops, in combination with a

resilient paper dish lining seated in said concavity with its edge beneath said stops, said dish lining comprising overlapping tongues lying against the end walls of said concavity, said dish lining being slit from its edge at opposite ends to provide said tongues, the lateral edges of said dish lining providing shoulders at each side of said stops. 70

4. A paper blank for dishes including a generally elliptical sheet longitudinally slit at each end from its edge, the opposite sides of said sheet being inwardly recessed. 75

5. A holder, for paper dishes and the like, comprising an elongated concavity the side and end walls of which each incline downwardly toward the center of the holder, the inclination of the end walls being steeper than that of the side walls, the end walls curving transversely of the holder, the side walls having inwardly extending dish stops, the bottom wall of said concavity inclining gently downwardly, in longitudinally opposite directions, from the central portion. 80 85 90

6. A holder, for paper dishes and the like, comprising an elongated concavity the side and end walls of which each incline downwardly toward the center of the holder, the inclination of the end walls being steeper than that of the side walls, the end walls curving transversely of the holder, the side walls having inwardly extending dish stops, the bottom wall of said concavity inclining gently downwardly, in longitudinally opposite directions, from the central portion and merging into both the side and end walls. 95 100 105

7. In a device of the character described, in combination, a holder including an elongated concavity the side and end walls of which incline downwardly toward the center of the holder, the inclination of the end walls being steeper than that of the side walls, the end walls curving transversely of the holder, the edge of said holder having inwardly extending stops, and a resilient paper dish lining removably seated in and generally conforming to said concavity with its edges beneath said stops, said dish lining including integral portions freely overlapping and lying against said end walls of said concavity. 110 115 120

8. In a device of the character described, in combination, a holder including an elongated concavity the side and end walls of which incline downwardly toward the center of the holder, the inclination of the end walls being steeper than that of the side walls, the end walls curving transversely of the holder, the edge of said holder having inwardly extending stops, and a resilient paper dish lining removably seated in and generally conforming to said concavity with its edges beneath said stops, said dish lining 125 130

including integral portions freely overlapping and lying against said end walls of said concavity, the edges of said dish lining having shoulders at each side of said stops.

5 9. In a device of the character described, in combination, a holder having walls and a bottom provided with an elevation intermediate said walls, a resilient dish lining for said holder tensioned across said elevation, 10 and means opposed to said tensioning for holding said dish lining in position.

10 10. In a device of the character described, in combination, a holder having walls, and a bottom provided with an elevation intermediate said walls, a resilient dish lining tending normally to assume a flat shape and having a divided edge portion providing tongues, said dish lining being bent across said elevation, said tongues being overlapped 20 against the resiliency of said dish lining and held in such relationship by engagement with said wall.

11. In a device of the character described, in combination, a holder having a cavity, a 25 wall for said holder, stops on said wall, a re-

silient dish lining in said cavity tending normally to assume a flat form and having a divided edge forming tongues, said tongues having overlapping portions adjacent said wall tending under the resiliency of said lining to move to unlapped position, said stops and said wall constituting the sole means for restraining the tendency of said lining to assume a flat shape and of said tongues to move to unlapped position. 30

12. A holder having an elongated concavity with the walls merging smoothly into each other, stops at opposite points on the walls, and a resilient paper lining in the concavity with its edges beneath the stops, the lining including overlapping contiguous portions lying against the end walls and so held by the resiliency of the lining. 40

In testimony whereof I affix my signature, in the presence of two witnesses.
